(57) **CLAIM**

I claim the ornamental design for a shark cartoon animal shape beach shoe, as shown and described.

DESCRIPTION

FIG. 1 is a front perspective view of a shark cartoon animal shape beach shoe showing my ornamental design;

FIG. 2 is a front view of a shark cartoon animal shape beach shoe showing my ornamental design;

FIG. 3 is a rear view of a shark cartoon animal shape beach shoe showing my ornamental design;

FIG. 4 is a right side view of a shark cartoon animal shape beach shoe showing my ornamental design;

FIG. 5 is a left side view of a shark cartoon animal shape beach shoe showing my ornamental design;

FIG. 6 is a top view of a shark cartoon animal shape beach shoe showing my ornamental design; and,

FIG. 7 is a bottom view of a shark cartoon animal shape beach shoe showing my ornamental design.

The broken lines in the drawings are used to illustrate portions of the invention that form no part of the claimed design.
